UNITED STATES PATENT OFFICE.

ALBERT W. HEINLE, OF CRAFTON, PENNSYLVANIA, ASSIGNOR OF ONE-HALF TO
SAMUEL E. DUFF, OF BEN AVON, PENNSYLVANIA.

METHOD OF ROLLING STRUCTURAL UNITS.

Application filed August 24, 1921. Serial No. 494,817.

The present invention relates broadly to metal working, and more particularly to metal rolling.

An important object of the present invention is to produce a flat, curved, angular or other structural unit having a predetermined taper or variation in thickness throughout the length thereof, which taper or variation may be in theoretical or practical accordance with the strength requirements of the article or structure to be formed therefrom.

Another object of the invention is to provide, by rolling, a structural unit having the characteristics set forth.

Still another object of the present invention is to form any desired number of structural units having either the thickness thereof only, or both the thickness and the width thereof, varying uniformly, progressively or intermittently throughout the longest dimension thereof.

A further object of the invention is to control the dimensions of the finished unit by employing a master pattern formed to provide the desired taper, curve, variation, or the like.

A still further object of the invention is to produce by cutting and rolling, a finished structural plate, bar or other unit having either a single or compound taper, curve, or other variation, respectively, in either the thickness thereof only, or in both the width and thickness.

The foregoing and other objects of the present invention, together with their attendant advantages, will be apparent as the invention becomes better understood by reference to the accompanying specification and drawings, forming a part thereof, it being premised that changes may be made in the various details and the manner of operation within the scope of the appended claims, without departing from the spirit of the invention.

In the drawings,—

Figure 1 is a plan view of a blank from which one form of structural unit may be produced in accordance with the present invention;

Figure 2 is a similar view of the blank cut to provide metal stock for two structural units;

Figure 3 is a plan view of the stock for one of the units prepared for rolling; 55

Figure 4 is a plan view of the stock for another form of unit;

Figure 5 is a diagrammatic view of one form of mechanism which may be utilized for carrying out the present invention; 60

Figure 6 is a diagrammatic plan view of a portion of the apparatus illustrated in Figure 5;

Figures 7 and 8 are longitudinal sectional views through modified forms of rolls which 65 may be utilized in accordance with the present invention;

Figures 9 and 10 are views corresponding to Figures 5 and 6, respectively, but illustrating a modified method of carrying out 70 the present invention; and

Figure 11 is a longitudinal sectional view through a modified form of master pattern.

In order to conserve material and produce a finished article having sufficient cross sectional area to withstand the maximum strains and stresses to which the article is subjected, it is necessary to produce a flat, curved, angular, or other shaped structural unit having either its width or both its width and thickness varying throughout the longest dimension of the unit, this variation being in accordance with the varying strength requirements of the finished article as theoretically or practically determined. Such units having one or more of their dimensions varying throughout the length thereof are useful, for example, in the construction of poles, posts, towers, tanks, and other forms of containers and similar constructions. By the present invention there may be produced by rolling a suitable metal stock, a structural unit having the desired shape to answer the requirements generally referred to. 85

Referring more particularly to the drawings, there is illustrated in Figure 1 a plan view of a rectangular billet 1, adapted to be cut along the diagonal dotted line 2 to separate the billet into two blanks 3 and 4 varying in width throughout their length, as indicated in Figure 2. Each of these blanks may thereafter have its ends trimmed so as 90

to extend at substantially right angles to the longitudinal center line thereof, as shown in Figure 3. This forms the metal 95

stock from which may be produced by the present invention a structural unit having both its width and its thickness varying throughout the longest dimension, as already set forth.

In accordance with one form of the present invention, the metal stock A, which is of constant thickness throughout its length but of varying width, is placed on a suitable roll table 5 adapted to deliver the same to the upper roll pass formed by the upper roll 6 and the middle roll 7 of a three-high mill of any desired construction. Mounted upon a second roll table 8 is a master pattern 9 having its thickness gradually varied either uniformly, progressively or intermittently throughout the major portion of its length, the end portions 10 thereof being of uniform thickness to prevent dropping of the rolls after the rolling of the metal stock has been completed. The master pattern is adapted to be fed through the lower roll pass formed by the intermediate roll 7 and the lower roll 11. It will be apparent that the rolls 6, 7, 11 and 12 may be driven in any desired manner, as is customary in mills of this nature, in such manner that the intermediate roll 7 is free to move upwardly or downwardly to an extent determined by the setting of the screw-down 12 for the upper roll.

In rolling the metal stock A, the mill and roll tables are first started to bring the master pattern into the position shown in Figure 5, in full lines, with the beginning of its main tapered body portion in the bite of the rolls constituting the lower roll pass. At this time one end of the metal stock A is brought into the bite of the rolls constituting the upper roll pass. Thereafter, continued operation of the mill will cause the intermediate roll 7 to be gradually raised in accordance with the increasing thickness of the master pattern, thereby decreasing the width of the upper roll pass and producing a corresponding decrease in the thickness of the metal stock passing therethrough. At the conclusion of the rolling operation, the pattern and stock, respectively, will be in the positions indicated by dotted lines in Figure 5, with the intermediate roll 7 raised to its dotted line position. At this time, the intermediate roll will be prevented from dropping by the thick end portion 10 of uniform cross sectional area. In cases where it is desired to produce a material variation in the thickness of the stock, it will be apparent that the number of rolling operations to which it is subjected may be increased as required.

The master pattern 9, as shown in Figure 6, will preferably have a width substantially greater than the width of the metal stock A and occupy the major portion of the roll surfaces, whereby tilting of the rolls and consequent uneven rolling of the metal stock is prevented. If desired, suitable air or

water sprays 13 may be provided for keeping the surface of the master pattern freed from scale and other foreign matter.

In the modification shown in Figure 7, each of the rolls 6', 7' and 11' is formed either with an angular circumferentially extending projection or depression 14, adapted to cooperate with an angular master pattern 9' and produce a structural unit A' angular in cross section.

With the modified form of rolls 6', 7' and 11' illustrated in Figure 8, there may be utilized a curved master pattern 9" adapted to produce a correspondingly shaped structural unit A".

Instead of utilizing metal stock A of constant or uniform thickness and varying width, I may start with a blank B, such as shown in Figure 4, having both its width and thickness uniform throughout its entire length. In such cases, there will be produced a structural unit having only the thickness thereof varying; while with metal stock A there will be produced a structural unit having both the thickness and the width varying. With either form of metal stock, however, it will be obvious that the edges of the finished unit may be sheared or otherwise trimmed, if necessary, and that either the upper or lower roll pass may receive the pattern.

The present invention may also be carried out by the use of a two-high mill constructed as indicated diagrammatically in Figures 9 and 10. Such a mill may comprise any desired type of roll housing 15 having a fixed lower roll 16 and a vertically adjustable upper roll 17 the movement of which may be regulated hydraulically, as by the use of a hydraulic cylinder 18. These cylinders may have any desired form of check controlled inlet and outlet, as will be readily apparent. Each of the rolls 16 and 17 is formed with necks 19 adapted to cooperate with master patterns 20, which may be connected in any desired manner, not shown, to cause the same to move in unison while the main body of the rolls intermediate the necks 19 is adapted to cooperate with the metal stock A' being rolled. With a mill of this type, it will be apparent that the master patterns and the metal stock are both fed into the rolls from the same side thereof, and that the rolls are continually forced together in accordance with the dimensions of the master patterns 20 above the pistons 18.

By the use of the present invention it is possible to produce economically, as by rolling, structural units of any desired cross sectional configuration having the cross section thereof varying throughout the length thereof in either one or more of its dimensions. For example, instead of providing a master pattern having a straight taper, as hereto-

fore referred to, there may be utilized a master pattern such as shown in longitudinal section in Figure 11, which comprises the end portions 21 of uniform thickness to prevent dropping of the rolls, and an intermediate body portion 22 abruptly curved or reduced in thickness adjacent one end and gradually tapering throughout the remaining portion thereof.

10 The stock being operated upon may be rolled while it retains the original heat, or it may be separately heated and then rolled, while the master pattern will be kept cool during the rolling operation.

15 By the term "structural unit" as used throughout the specification and claims, I intend to include any structural bar, plate, rod, or other shape adapted to form a complete article of sale or to be used as part of 20 a composite structure.

25 The advantages of the present invention arise from the method of producing structural shapes by rolling, which possess the desired strength requirements without having any excess or unnecessary metal.

I claim:

1. The method of forming structural units, comprising subjecting metal stock to the action of rolls in a single roll pass, controlling

the distance between the roll surfaces by a 30 master pattern passing between the rolls, and providing guiding means for said master pattern, substantially as described.

2. The method of forming structural units, comprising forming a blank of uniform cross 35 sectional area throughout the length thereof, splitting said blank diagonally to produce blanks of uniform thickness and varying width, subjecting one of said last mentioned blanks to the action of rolls in a roll pass, 40 and varying the distance between the roll centers throughout the rolling operation to vary the thickness of said blank as desired, substantially as described.

3. The method of forming structural units, 45 comprising cutting a substantially rectangular billet diagonally to produce a plurality of blanks having a substantially uniform thickness and varying widths, squaring the ends of said blanks, subjecting said blanks 50 to the action of rolls in a roll pass, and varying the distance between the roll centers in accordance with the variations desired in the thickness of the finished unit produced from said blank, substantially as described. 55

In testimony whereof I have hereunto set my hand.

ALBERT W. HEINLE.
